(57) **CLAIM**

The ornamental design for a toothbrush sterilizer, as shown and described.

DESCRIPTION

1. Toothbrush sterilizer

Fig. 1.1 is a top, front and right side perspective view of the design;

Fig. 1.2 is a bottom, front and right side perspective view of the design;

Fig. 1.3 is a front elevational view of the design;

Fig. 1.4 is a back elevational view of the design;

Fig. 1.5 is a left side elevational view of the design;

Fig. 1.6 is a right side elevational view of the design;

Fig. 1.7 is a top plan view of the design;

Fig. 1.8 is a bottom plan view of the design; and

Fig. 1.9 is an exploded top, front, and right side perspective view of the design.
